Charles W. Bereth
John A. Rainsmith

ATTORNEY

UNITED STATES PATENT OFFICE.

CHARLES W. BERETH, OF SAN JOSE, CALIFORNIA.

AWNING.

Application filed August 11, 1927. Serial No. 212,252.

When it is desired to place an awning of the type now commonly in use over a casement window, a French window, or any outwardly swinging closure for a wall opening, 5 it is necessary to mount it upon the wall some distance above the head casing of the opening in order to permit the closure to swing outwardly without striking the top of the awning. Since the placing of the awning so 10 high up on the wall is unsightly and to some extent inefficient and damaging to the wall, they are ordinarily omitted altogether.

It is the object of the present invention to provide an awning construction that will 15 permit mounting the awning upon the casing of the wall opening as desired and at the same time permit swinging the closure outwardly in the usual way without injuring the awning or interfering with the proper functioning 20 thereof.

It is also an object of the invention to provide an awning of the character indicated provided with a movable section operated by movement of the closure, and one that will 25 be simple in form, economical to manufacture and highly efficient in its practical application.

In the drawing:

Figure 1 is a perspective view of a portion 30 of an awning embodying my invention in position.

Figure 2 is a perspective of a portion of the structure shown in Figure 1.

Referring now more particularly to the 35 drawing, I show at 1 an awning of the usual type mounted upon the window casing 2, outwardly swinging windows being shown at 3 and hinged at 4.

In effecting my invention I provide an 40 opening 5 in the top of awning 1 of such a size as to permit the window 3 to swing open therethrough, as shown in Figure 1. I then provide a wire frame as 6 of slightly larger dimensions than the opening 5 and having 45 hooks formed on its two ends as shown at 7, these hooks engaging eyes 8 set in the casing 2 so that the frame 6 may swing upwardly about the eyes as pivots.

At 9 I show a link clamped to the frame 6 50 in any suitable manner as at 10 and at a point adjacent the end above the hinged edge of the window. The other end of the link is attached to the window sash adjacent its hinged edge and below the eyes 8 by means of inter-

engaging hook and eye construction where- 55 by a pivotal movement of the link is permitted at 11.

An auxiliary awning is provided at 12 and mounted on the frame 6, its upper edge being attached to the main awning and its lower 60 edge having a pendant portion 13 weighted in any suitable manner as by attaching weights as 14 to its lower edge.

By means of this construction when the hinged window is closed as at 3^a the auxiliary awning lies flat upon the large awning as at 12^a completely and effectually closing the opening 5. When, however, the window is swung open about its hinges 4, then the link 9 is pushed outwardly and upwardly 70 because it is positioned eccentrically to the hinges 4, and through its attachment to the frame 6 it pushes the said frame and the awning carried thereby upwardly into the position shown in Figure 1 so that the window itself may swing clear open beneath it. When the window is closed again the action is reversed, and the weighted edge 14 is drawn down flat upon the awning 1. 75

By means of this construction the awning 80 may be mounted upon the window or door casing in the usual manner.

It is to be understood, of course, that while I have herein shown and described one specific embodiment of the invention, changes 85 in form, construction, and method of operation may be made within the scope of the appended claims, it being obvious that any suitable type of frame 6 may be provided, and any suitable means may be provided for connecting the link 9 to the frame and door. 90

I claim:

1. An awning for a wall opening having a swinging closure mounted therein comprising, an awning member adapted to be mounted upon the wall immediately over the opening therein, and having an opening in its upper surface, an auxiliary awning mounted to normally close the opening in the awning member, and means mounted on the auxiliary awning and adapted to be eccentrically attached to the swinging closure whereby opening the closure will move the auxiliary awning to an open position relative to the opening in the awning member. 95

2. An awning for a wall opening having a swinging closure mounted therein comprising, an awning member adapted to be mount-

ed upon the wall immediately over the opening therein, and having an opening in its upper portion to permit the passage of a portion of the closure therethrough, an auxiliary awning hingedly mounted to normally close the opening in the awning member, and a link eccentrically mounted on the auxiliary

awning and adapted to be eccentrically mounted upon the swinging closure whereby opening the closure will actuate the auxiliary awning to an open position relative to the opening in the awning member. 10

CHARLES W. BERETH.
